Specification for Design.

Patented Sept. 5, 1916.

Application filed May 3, 1916. Serial No. 95,733. Term of patent 3½ years.

To all whom it may concern:

Be it known that I, DENNIE W. GIST, a citizen of the United States, residing at Kansas City, in the county of Jackson and State of Missouri, have invented a new, original, and ornamental Design for a Phonograph or Talking-Machine Cabinet, of which the following is a specification, reference being had to the accompanying drawing, forming part thereof.

The figure is a perspective view of a pho-

nograph or talking machine cabinet, showing my new design.

I claim:

The ornamental design for a phonograph or talking machine cabinet, as shown.

In witness whereof, I have affixed my signature in the presence of two witnesses.

DENNIE W. GIST.
